WARP BEAM LIFTING MECHANISM FOR LOOMS

Clarence R. Kronoff, Worcester, Mass., assignor to Crompton & Knowles Loom Works, Worcester, Mass., a corporation of Massachusetts

Application July 27, 1946, Serial No. 686,783

19 Claims. (Cl. 139—1)

1

This invention relates to improvements in lifting mechanism for the warp beams of looms, and it is the general object of the invention to provide simple and efficient chain operated means to lift the beam and move its gudgeons toward loom supported bearings.

Looms operate with a beam at the rear thereof on which the warp threads are wound. When these beams are of relatively large diameter they attain considerable weight and it is desirable to provide mechanical means by which the beam can be lifted into operating position on the loom. It is an important object of my present invention to provide chain operated means for lifting the beam in cooperation with sprocket wheels secured to the beam.

In an application Serial No. 686,294 filed July 26, 1946, by Sepavich and myself there is set forth a let-off mechanism employing motor driven chains to regulate the amount of feed of the warp. These chains mesh with sprocket wheels on the warp beam and are driven by a motor to rotate the beam to deliver warp. It is another object of my present invention to utilize the motor which drives the let-off chains for the purpose of raising the beam and thereby relieve the weaver of heavy manual labor incident to placing a full beam in the loom.

The aforesaid let-off chains engage the forward part of the beam sprocket wheels and must be taut for letting off purposes. It is another object of my invention to cause the let-off chains to automatically tighten themselves as they complete the beam lifting operation. Loom supported chains meshed with the beam sprocket wheels facilitate this automatic tightening.

The chains of the let-off mechanism are normally slack except when the warp beam is in operating position. During the preliminary stages of the lifting operation the sprocket wheels will engage slack parts of the let-off chains. It is another object of my present invention to provide chain tightening means for increasing the wrap of the let-off chains around the sprocket wheels when the chains are slack to facilitate raising of the beam. The tightening means are preferably manually operated so that the attendants will be able to control the motion of the beam.

It is another object of my invention to provide electric switch control means for the motor located in a position readily accessible to at least one of the attendants for the purpose of causing the motor to run both reversely for lifting the beam and forwardly for slackening the

2

supporting chains, or lowering the beam should it by any circumstance attain too high a position in the loom.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of the rear part of the loom having my invention applied thereto, parts being in section,

Fig. 2 is a plan view looking in the direction of arrow 2, Fig. 1,

Fig. 3 is a detailed bottom plan on an enlarged scale looking in the direction of arrow 3, Fig. 1,

Fig. 4 is a detailed plan view looking in the direction of arrow 4, Fig. 1, showing the manner of attaching the upper end of a holding or beam supporting chain to the loom frame,

Figs. 5 and 6 are diagrammatic views illustrating the operation of the invention,

Fig. 7 is a diagrammatic view of the electric circuits used with my invention, and

Fig. 8 is a diagrammatic plan view of the mechanism indicating both sides of the loom and showing the differential mechanism which may be used with the invention.

Referring particularly to Figs. 1, 2 and 8, I have shown a loom frame 10 having a warp beam 11 which supplies warp W. Ordinarily the warp is trained over a whip roll 12 and then extends forwardly through various weaving instrumentalities one of which is indicated at the harness frames 13. Each side of the loom frame has extending rearwardly therefrom a bearing 14 one of which is shown in Fig. 2. The lower fixed socket 15 of each bearing opens upwardly and rearwardly, and a gudgeon support 16 on each bearing has an inclined surface extending downwardly and rearwardly from the corresponding socket for engagement with the associated beam gudgeon 17. Cap bearings 18 one of which is shown in Figs. 1 and 2 can be thrown upwardly to the position shown in Fig. 1, when a beam is to be placed in the loom, but ordinarily they are closed around the gudgeons.

The loom is provided at each side thereof with a system of guide sprocket wheels only one system of which is shown in detail in the drawings. The system set forth in Figs. 1 and 2 includes an upper rear lifting sprocket wheel 20 rotatable on a stand 21 fixed to the loom frame, an upper forward sprocket wheel 22 also rotatable on stand

30

40

45

50

55

21, and a lower or bottom sprocket wheel 23 rotatable on support 24. These sprocket wheels mesh with a chain 25 which is ordinarily tight when the beam is in operating position, but will be slack when the beam is out of the loom. The chain has a front section 26 and a rear section 27 to engage a driven or beam sprocket wheel 28 secured to the beam concentrically with gudgeon 17. Each side of the loom will have one of these chain and sprocket wheel systems.

The sprocket wheel and chain systems form part of the loom letoff mechanism which is driven by a motor M. This motor is operatively connected to a speed reducing unit 30 which is operatively connected to a differential mechanism D shown diagrammatically in Fig. 8. Two shafts 31, one for each system, are driven by mechanism D and are rotatable on the loom frame. Each shaft 31 has secured thereto a pinion 32 which meshes with a gear 33 secured to a front upper sprocket wheel 22. The connections between the motor and the chains 25 are such that when the motor is driven forwardly as set forth in the aforesaid application, due to the increase in warp tension, the chains will travel in a counter-clockwise direction as viewed in Fig. 1, thereby causing clockwise rotation of the warp beam to deliver warp for the weaving process. This is the normal operation of the motor and chains when the loom is weaving, but for the purposes of my present invention the motor is controlled so that it can be reversed for the purpose of raising the rear chain sections 27.

The warp beam includes a barrel 35 to which are secured heads or flanges 36 between which the warp W is wound. For convenient manipulation of the beam a form of truck or dolly 40 is provided as indicated in Fig. 1. The particular form of the dolly forms no part of my present invention, but it may include front and back parallel members 41 to support flanges 36, and have side members 42 and be mounted on rollers 43.

Except as noted hereinafter the matter thus far described may be as set forth in the previously mentioned copending application. The motor drives the differential mechanism which in turn causes equal forces to be exerted by shafts 31 on the chains 25.

In carrying my invention into effect I provide support means for the rear part of the beam which will cooperate with chain sections 27 to lift the beam. This support means effectively prevents free rotation of the warp beam by the chains 25 and in the present instance comprises chains 45 which, as shown in Fig. 4, terminate at their upper ends in hooks 46 connectable to small supports or stands 47 secured to the loom frame.

The lower end of each chain 45 may be provided with some means for securing it to the corresponding sprocket wheel 28. As indicated in Fig. 3 two of the chain links 50 and 51 are bridged by a bolt 52 having a winged nut 53. The bolt passes through the holes usually provided for the cross bars of the chain, and when the wing nut is tightened the links 50 and 51 are clamped against the sprocket wheel 28. I do not deem it essential in all forms of my invention to use the structure shown in Fig. 3, since under some conditions adequate support for the rear part of the beam will be derived from the meshing of each chain 45 with the rear part of its sprocket wheel 28.

Each bearing 14 has fixed thereto a stud 55 to receive a removable lever 56. Each lever has a handle 57 on the upper end thereof and a shoe

58 on the lower end thereof for engagement with the associated rear chain section 27. The shoes are below the axis of the beam when the latter is in the position shown in Fig. 1. Both chains 5 and 45 and the levers 56 are removable from the loom and can be moved from one loom to another by the attendants who mount the beams on the loom.

The motor M may be controlled by circuits shown diagrammatically in Fig. 7. The motor 10 has an armature 60 and a field coil 61 and is supplied by direct current from power lines 62 and 63. A gang switch GS controls the operation of the motor and in the present instance includes upper and lower field coil blades 65 and 66, respectively, and upper and lower armature blades 67 and 68. These blades are connected together by an insulated cross bar 69 having a handle 70 by which all of the blades may be manipulated, and the blades tend normally to assume the neutral position shown in which they will be out of engagement with their respective contacts.

The switch GS affords means for driving the motor either forwardly or backwardly, and when raised the following field coil circuit is closed: wires 62 and 71, blade 65, contact 72, wire 73, 25 field coil 61, wire 74, contact 75, blade 66 and wire 76 to the other power line 63. At the same time the following armature circuit is closed: power line 62, wire 71, blade 67, contact 77, wire 78, armature 60, wire 79, contact 80, blade 68 and wire 76 back to power line 63. When the blades are up current flows to the right through both the field and the armature, and it may be assumed that this corresponds to forward running of the motor.

35 When handle 70 is depressed the blades engage the contacts on the under side thereof, contacts 82 and 83 causing current to flow through the field coil in the same direction, but contacts 85 and 86 causing current to flow through the armature in a reverse direction to reverse the direction of the motor.

In the previously mentioned copending application the circuits are such that they are open when the loom is stopped, and the circuits shown 45 in Fig. 7 can therefore be used without conflicting with any of the circuits which are in control of the motor M when it is used to operate the letoff mechanism of the loom.

The switch GS may conveniently be located on some part of the loom accessible to one or another of the attendants when the beam is being placed in the loom. For convenience I illustrate a switch box 90 mounted on one of the bearings 14 in position where it can be controlled by the same attendant who operates the adjacent lever 56.

When a beam is to be applied to the loom it will be rolled to the position shown in Fig. 1 by means of the dolly 40 and placed with its gudgeon 17 close to or in engagement with the inclined surfaces on supports 16. In this position the front part of the sprocket wheels 28 will mesh with the slack rear chain sections 27. The chains 45 will then be hooked over their supports or stands 47 and if desired have their lower ends secured to the corresponding sprocket wheels 28 after being wrapped around the rear parts of the latter.

There will ordinarily be two attendants for 70 handling the beam, and each attendant will then move his lever 56 to effect engagement of the lower part of the adjacent slack chain section 27 with the teeth of the sprocket wheel 28 adjacent thereto. When driving connection has thus been established between the chains 25 and the sprocket

wheels 28 one of the attendants will depress the switch handle 10 to effect reverse motion of the motor M and the latter, acting through the speed reducer 30 and the differential D and shafts 31, will cause a clockwise movement of the chains 25 as viewed in Fig. 1. As the rear chain sections 27 rise they will lift the beam and its gudgeons 17 will move along supports 16 toward the sockets 15, see Fig. 5. It will be noted that the upper parts of chain sections 27 and the chains 45 are forward of the axis of the sockets 15, and it is for this reason that the beam tends to move forwardly as it rises so that the gudgeons eventually enter the sockets 15, as shown in Fig. 6.

The differential mechanism insures the delivery of equal forces to each side of the beam and the gudgeons will enter their sockets at approximately the same time. If for any reason one gudgeon should enter its socket ahead of the other its socket will resist further upward movement and the differential will continue to exert a lifting force on the other gudgeon until the latter has entered its socket.

When both gudgeons are in their sockets the switch GS will be released and will return to its normal mid or neutral position in which it is out of engagement with all of its contacts and both the armature and the field coil will be dead. Under these conditions it may be that the chains 45 will be held tightly, but a slight forward movement of the motor effected by raising the handle 10 for a brief interval of time will cause counter-clockwise movement of the chains 25 which will slacken the chains 45 and the latter can be removed. This last operation may take place either before or after the cap bearings 18 have been secured in their normal positions.

The attendants will ordinarily need to exert only a slight force on the levers 56 to insure proper meshing of the chain sections 27 with the sprocket wheels 28, and the beam by its weight will overcome this slight force and will rock the levers in a counter-clockwise direction as viewed in Fig. 1 against the hands of the attendants as the chains 25 tighten.

From the foregoing it will be seen that I have provided simple means by which a warp beam can be applied to a loom by means including chains. These chains may conveniently be parts of the loom letoff mechanism, although it is evident that so far as certain features of my invention are concerned the chains 25 need not necessarily be parts of a letoff mechanism. It will also be seen that the rear parts of the sprocket wheels 28 are held against downward motion during the beam lifting operation, the means for accomplishing this result as set forth hereinbefore being the chains 45, but I do not wish necessarily to be limited in all applications of my invention to the use of these chains. Both the chains 45 and the levers 56 are removable and can be moved from loom to loom, the only parts permanently added to the loom for the use of the invention being the supports 47 and the studs 55. Furthermore, the upper ends of the chains 45 and chain sections 27 are forward of the axis of the bearing sockets 15 and for this reason the gudgeons 17 tend to move forwardly as they slide up the inclined guiding surfaces 16 of the bearings 14. The movement of the gudgeons into their sockets is therefore accomplished automatically by power derived from the motor M. The levers 56 are useful in most applications wherein the rear chain sections 27 might tend to become disengaged with the front parts of the sprocket wheels 28 during the

beginning of the warp lifting operation, but I am not necessarily limited in the use of my invention to these levers 56, since a slight change in the position of the bottom sprocket wheels 23 5 rearwardly from the position shown in Fig. 1 would suffice to insure adequate mesh between the sprocket wheels 28 and the slack rear chain section 27. Also, the gang switch GS is located in a position readily accessible to at least one of the attendants and can be utilized not only to effect reverse motion of the motor necessary to lift the beam, but also forward movement of the motor to slacken the chains 45, or if need be to lower the beam should its gudgeons by any circumstance have moved to a position above the sockets 15. Furthermore, the letoff chains automatically tighten themselves at the end of the beam lifting operation in readiness for operation of the letoff mechanism.

Having thus described my invention it will be seen that changes and modifications may be made therein by those skilled in the art without departing from the spirit and scope of the invention and I do not wish to be limited to the details herein disclosed, but what I claim is:

1. In lifting mechanism for the warp beam of a loom having a bearing to receive a gudgeon on the beam, a guide extending below the bearing, a sprocket wheel on the beam, a sprocket chain 30 movably mounted on the loom engaging the sprocket wheel on one side of the axis thereof, and means supporting the beam on the other side of said axis and cooperating with the chain when that part of the latter meshed with the sprocket 35 wheel is raised to lift the beam and move the gudgeon along said guide toward said bearing.

2. In lifting mechanism for a warp beam having a gudgeon to be received by a bearing on a loom, a guide for the gudgeon extending downwardly and rearwardly from the bearing, a lifting chain 40 movably mounted on the loom, a sprocket wheel on the beam having the front part thereof meshing with said lifting chain, means supporting the rear part of the sprocket wheel 45 in such manner that the beam tends to move forwardly to keep the gudgeon against the guide as the beam rises, and means operatively connected to the chain to raise that part of the latter meshed with the sprocket wheel and cause said chain and supporting means to cooperate to move the gudgeon along said guide toward said bearing.

3. In lifting mechanism for the warp beam of a loom having a bearing to receive a warp beam gudgeon, sprocket wheels rotatably mounted on the loom, a chain meshing with said sprocket 55 wheels, a beam sprocket wheel on the warp beam meshing with said chain forward of the axis of the beam, support means secured to the loom forward of the axis of the beam and operatively connected to the latter behind said axis, and means to raise that part of the chain meshed with said beam sprocket wheel to cause the latter to cooperate with said supporting means to lift the beam and move the gudgeon forwardly toward said bearing.

4. In lifting mechanism for a warp beam having a gudgeon below and rearward of a bearing on a loom, a plurality of loom supporting sprocket wheels, a lifting chain meshing with said sprocket 60 wheels, a beam sprocket wheel on the beam meshing with said chain in front of the axis of the beam, a supporting chain having one end thereof secured to the loom forward of the axis of the beam and meshing with the beam sprocket wheel 65 rearwardly of said axis, and means to move said

lifting chain in such direction that said chains cooperate to lift the beam and move the gudgeon forwardly toward the bearing.

5. In lifting mechanism for the warp beam of a loom having a bearing to receive a gudgeon on the beam, upper and lower guide sprocket wheels rotatable on the loom, one above and the other below the axis of the beam, a chain having a rear section meshing with said sprocket wheels, a beam sprocket wheel on the beam having the forward part thereof meshing with said section of the chain between said upper and lower guide sprocket wheels, means supporting the rear part of the beam, and means to turn the upper sprocket wheel to raise said section of the chain to lift the beam and move the gudgeon toward the bearing.

6. In lifting mechanism for the warp beam of a loom having a bearing for the beam gudgeon and a gudgeon guide inclined downwardly and rearwardly from the bearing, a sprocket wheel on the beam, two chains meshing with said sprocket wheel, one chain on one side of the axis of the sprocket wheel and the other chain on the other side of the axis of the sprocket wheel, means holding the upper end of one of said chains to the loom above and forwardly of the axis of the bearing when the gudgeon engages said guide below the bearing, and means locating the upper end of the other chain above and forward of said bearing axis and effective to raise said other chain and cause said chains to cooperate to lift the beam and cause the gudgeon to move along said guide to said bearing.

7. In lifting mechanism for the warp beam of a loom having a bearing to receive a gudgeon on the beam, a loom supported sprocket wheel, a chain meshing with said wheel and having a normally slack rear section depending from the sprocket wheel, a beam sprocket wheel on the warp beam meshing with said rear section of the chain when the latter is slack, means engaging said rear section of the chain causing the latter to wrap around a forward part of the beam sprocket wheel, means supporting the rear part of the beam, and means to raise said chain section to lift the forward part of the beam sprocket wheel to raise the beam and move the gudgeon toward the bearing.

8. In lifting mechanism for the warp beam of a loom having a bearing to receive a gudgeon on the beam, a plurality of loom supported sprocket wheels, a chain meshing with said wheels having a rear slack section, a beam sprocket wheel on the warp beam behind and meshing with said section of the chain, a shoe engaging part of said section of the chain forwardly of and below the axis of the beam sprocket wheel and holding said part of said section against the beam sprocket wheel, means supporting the rear part of the beam, and means to raise said section of the chain to lift the beam and move the gudgeon toward the bearing.

9. In lifting mechanism for the warp beam of a loom having a bearing to receive a gudgeon on the beam, a plurality of loom supported sprocket wheels, a chain meshing with said wheels and having a rear slack section, a beam sprocket wheel on the warp beam meshing with said section of the chain, manually operated means effective to hold part of said slack section of the chain below the axis of the beam sprocket wheel against the latter, means supporting the beam at a point behind the axis thereof, and means to lift said section of the chain to raise the beam and move the gudgeon toward the bearing.

10. In lifting mechanism for the warp beam of a loom, a sprocket wheel on the beam, a chain movably mounted on the loom and meshing with the sprocket wheel on one side of the axis thereof, means supporting the beam on the other side of said axis, an electric motor operatively connected to the chain, and electric circuit means effective to cause the motor to raise that part of the chain meshing with the sprocket wheel and cause said chain to cooperate with said supporting means to lift the beam.

11. In lifting mechanism for the warp beam of a loom, a sprocket wheel on the beam, a chain movably mounted on the loom and having a section meshing with the sprocket wheel on one side of the axis thereof, an electric motor operatively connected to the chain, means supporting the beam on the other side of said axis, and electric circuit means controlling the motor and effective to cause the latter either to raise said section of the chain to lift the beam or cause the motor to lower said section of the chain to lower the beam.

12. In lifting mechanism for the warp beam of a loom, a sprocket wheel on the beam, a chain movably mounted on the loom and having a section meshing with the sprocket wheel on one side of the axis thereof, means supporting the beam on the other side of said axis, an electric motor operatively connected to the chain, reversible switch means, and electric circuit means including the motor and switch means and effective when the latter is in one position to cause said motor to raise said section of the chain and effective when the switch means is in another position to cause the motor to lower said section of the chain.

13. In lifting mechanism for the warp beam of a loom, a sprocket wheel on the beam, a chain movably mounted on the loom and having a section meshing with the sprocket wheel on one side of the axis thereof, means supporting the beam on the other side of said axis, manual means to hold part of said section of the chain below said axis against the sprocket wheel, an electric motor operatively connected to the chain, manually controlled electric switch means adjacent said manual means, and electric circuit means including said motor and switch means effective to cause said motor to raise said section of the chain while said section is held against said sprocket wheel by said manual means.

14. In a loom having a warp beam and letoff mechanism including a chain movably mounted on the loom, a sprocket wheel secured to the beam concentrically of the axis thereof and meshing with the chain on one side of said axis, means on the loom supporting the beam on the other side of said axis, and driving means for the chain forming part of the letoff mechanism and effective to raise that part of the chain meshed with the sprocket wheel to effect bodily movement of the beam upwardly with respect to the loom.

15. In a loom having a letoff mechanism employing a sprocket chain which must be tight for normal letting-off operations with respect to a warp beam when a gudgeon on the latter is in a loom bearing, a sprocket wheel on the warp beam having a part of one side of the axis thereof meshed with the chain when the gudgeon is below the bearing and the chain is slack, means supporting the beam on the other side of said axis, and means to raise that part of the chain meshed with the sprocket wheel when the chain

is slack to effect movement of the gudgeon into the bearing to effect tightening of the chain.

16. In a loom having a letoff mechanism employing a sprocket chain which must be tight for normal letting-off operations with respect to a warp beam when a gudgeon on the latter is in a loom bearing, a sprocket wheel on the warp beam having a part of one side of the axis thereof meshed with the letoff chain when the gudgeon is below the bearing and the chain is slack, a supporting chain having the upper end thereof attached to the loom and having the lower part thereof meshed with the beam sprocket wheel on the other side of said axis, and means to raise that part of the letoff chain meshed with the sprocket wheel when the letoff chain is slack to effect movement of the gudgeon into the bearing to effect tightening of the letoff chain.

17. In a loom having a letoff mechanism employing a sprocket chain which must be tight for normal letoff operations with respect to a warp beam when a gudgeon on the latter is in a loom bearing, a gudgeon guide on the loom depending from the bearing forward of the gudgeon, a sprocket wheel on the warp beam having a part of one side of the axis thereof meshed with the letoff chain when the gudgeon is below the bearing and against said guide and the chain is slack, a supporting chain having the upper end thereof connected to the loom forward of said axis and having the lower part thereof meshed with part of the beam sprocket on the other side of said axis, and means to raise that part of the letoff chain meshed with the sprocket wheel when the letoff chain is slack to effect movement of the gudgeon into the bearing to effect tightening of the letoff chain.

18. In a loom having a letoff mechanism employing a sprocket chain which must be tight

for normal letting off operations with respect to a warp beam when the gudgeon on the latter is in a loom bearing, a gudgeon guide in front of the gudgeon extending downwardly and rearwardly from the bearing, a sprocket wheel on the warp beam having a part of one side of the axis thereof meshed with the letoff chain when the gudgeon is below the bearing and in engagement with the guide and the chain is slack, supporting means attached operatively to the beam on the other side of said axis and attached to the loom at a point above and forwardly of said axis, and means to raise that part of the letoff chain meshed with the sprocket wheel when the letoff chain is slack to effect movement of the gudgeon upwardly along said guide into the bearing to effect tightening of the letoff chain.

19. In a loom having a letoff mechanism employing a sprocket chain having a vertically extending rear section which must be tight for normal letting off operations with respect to a warp beam when a gudgeon on the latter is in a loom bearing, a gudgeon guide on the loom extending downwardly and rearwardly from the bearing, a sprocket wheel on the warp beam having a part on one side of the axis thereof meshed with the letoff chain when the gudgeon is below the bearing and in engagement with the guide and said section of the chain is slack, the upper part of said chain section being above and forward of said axis, a supporting chain attached to the loom above and forwardly of said axis and having part thereof meshed with that side of the beam sprocket on the other side of said axis, and means to raise said section of the chain when the latter is slack to effect movement of the gudgeon along said guide into the bearing to effect tightening of said section.

CLARENCE R. KRONOFF.
